UNITED STATES PATENT OFFICE.

RONALD F. McFEELY, OF BEVERLY, MASSACHUSETTS, ASSIGNOR TO UNITED SHOE MACHINERY COMPANY, OF PATERSON, NEW JERSEY, AND BOSTON, MASSACHUSETTS, A CORPORATION OF NEW JERSEY.

PULLING-OVER MACHINE.

1,029,387.

Specification of Letters Patent. Patented June 11, 1912.

Application filed March 28, 1903. Serial No. 149,966.

To all whom it may concern:

Be it known that I, RONALD F. McFEELY, a citizen of the United States, residing at Beverly, in the county of Essex and Commonwealth of Massachusetts, have invented certain Improvements in Pulling-Over Machines, of which the following description, in connection with the accompanying drawings, is a specification, like reference characters on the drawings indicating like parts in the several figures.

This invention relates to pulling-over machines, which are used for preparing boots or shoes for lasting by performing the operation known as "pulling-over", and the invention is shown as applied to the machine illustrated in United States Letters Patent No. 663,777, granted December 11, 1900, and No. 950,701, granted March 1, 1910, and No. 20 988,582, granted April 4, 1911, and an application, Serial No. 532,681, originally filed Jan. 31, 1903.

An important feature of this invention is a heel-rest for the last, to resist backward strain upon the last. This backward strain is produced mainly by the grippers, especially the toe grippers, in drawing the upper over the bottom of the last. The wipers for wiping the upper over the edge of the last and the fastener inserting mechanisms which drive the securing tacks in a direction inclined inwardly from the edge of the last also contribute to the force tending to move the last backwardly. Heretofore it has been necessary for the workman to grasp the shoe at the heel with one hand and hold it against this backward strain. This called for a hand operation and taxed the strength of the workman. Moreover, it has proved to be impracticable for the workman to hold the shoe with sufficient force to prevent it from slipping back more or less as the several mechanisms forced the upper into place and secured it. These disadvantages have been obviated by the heel-rest of my present invention.

One of the problems which had to be dealt with in constructing a device of this character was due to the great variance in the shapes of lasts. To secure the best results and avoid loss of time in making adjustments, it is important that the heel-rest be self-adjusting to rights and lefts of various shapes of lasts, so that whatever the shape

or position of the heel of the last, the heel-rest will automatically position itself properly in the normal operation of the machine. It is also desirable that after the proper position of the heel-rest has been obtained, it be locked in such position during the pulling and securing operations, and that it be unlocked immediately after the completion of such operations. This locking and unlocking will preferably be effected automatically.

For securing the above-mentioned objects and overcoming the difficulties important features of this invention are concerned with the movably mounted heel rest. In the illustrated construction embodying these features the heel rest is so mounted that, while normally occupying a central position, it can move laterally to accommodate itself to the position of the heel of the shoe that is presented to the machine. I have also provided means for locking said rest against lateral displacement during the operation of the machine, said locking means being made operative, after the heel-rest has been positioned laterally, by the pressure of the shoe against the heel-rest, and being rendered inoperative when such pressure ceases.

In the embodiment of my invention herein shown the heel-rest occupies a retracted, inoperative position when the machine is at rest, and one feature of my invention consists in providing means which, when the machine is started, yieldingly advances the heel-rest into operative position against the last, but preferably without materially moving the last. As said rest meets the heel of the last it is automatically moved laterally into position to engage properly the heel end of the last, and is then automatically locked in such lateral position until the pulling-over operation is completed, after which it is retracted and unlocked and permitted to resume its normal central position.

Another feature of my invention consists in providing mechanism by which the heel-rest may be locked against rearward movement and also by which it may be actuated for giving the last a slight, positive forward movement after the upper has been stretched and while it is held taut by the grippers, thereby to "set" the shoe by forcing the last into the fore-part of the upper and causing the upper to conform to the lines of the

last, particularly along the top of the last from the toe toward and over the instep. In the construction herein shown provision is made for automatically operating the said 5 heel-rest actuating mechanism as above described during the regular operation of the machine, and mechanism is also provided by which the heel-rest may be further actuated manually in case the movement automatically 10 imparted to it is not sufficient, in a particular instance, to accomplish the desired result.

Another important feature of my invention 15 consists in means for positioning the inner-sole on the last. It is very desirable that the inner-sole be properly positioned on the last with its toe end flush with the toe end of the last. In assembling the upper and inner-sole upon the last it is customary, 20 particularly in the cheaper grades of shoes, for the workman to position the inner-sole loosely upon the last with the heel end against the upstanding portion of the counter or the upper at the heel of the shoe, and 25 frequently the inner-sole is not long enough to reach quite to the toe end of the last. Also the inner-sole may be so placed on the last that it extends too far forward and requires to be moved backwardly. I have, 30 therefore, provided means for moving the inner-sole either forwardly or backwardly upon the last.

In the embodiment of my invention herein shown the inner-sole is moved by means 35 of the rest against which the shoe is held bottom upwardly during the pulling-over operation. Preferably this rest, hereinafter called the "sole-rest", will be actuated automatically for moving the inner-sole at the 40 proper time and in the desired direction during the regular operation of the machine. I have also provided means by which the sole-rest may be moved manually after the automatic movement and while the machine is at rest if, upon inspection, the workman finds that the inner-sole has not been 45 properly positioned. Provision is made for controlling the direction of the automatic movement of the sole-rest so as to move the inner-sole either forwardly or backwardly. Provision is also made for varying the extent of the automatic movement of the sole-rest and for discontinuing said movements when it is not desired to have the sole-rest 50 automatically actuated. When the automatic movements of the sole-rest have been discontinued the rest may be manually actuated as desired for adjusting the inner-sole upon the last.

60 In the embodiment of my invention herein shown I have arranged the mechanisms for manually moving the sole-rest and the heel-rest so that they may be actuated by a single hand lever. The mechanisms for 65 manually operating the heel-rest and the

sole-rest constitute important features of my invention. In the preferred form these mechanisms are so constructed and arranged that the sole-rest may be moved either forwardly or backwardly at the will of the workman or that the two rests may be moved forwardly together. The workman is thus enabled manually to re-arrange the assembled parts of the shoe by forcing the last farther forward into the upper as the latter is held by the grippers. This may be done by the heel-rest or, in welt work or other high grades of work in which it is customary to tack the inner-sole to the last, the last may be adjusted either backwardly or forwardly by moving the sole-rest, which in moving the inner-sole moves with it the last which is secured to the inner-sole.

Other important features of my invention consist in the improved devices for supporting the last for the driving of the fastenings which secure the upper to the inner-sole, for wiping and pressing the pulled portions of upper over upon the inner-sole at the sides of the shoe, into position to receive said fastenings, and for holding said portions of the upper from slipping back during the interval between the opening of the grippers and the driving of the fastenings, together with the mechanisms for actuating said devices. It is my object to imitate as nearly as possible with these devices the operation of a skilful hand workman who, while supporting the shoe in his hand, uses his thumb to wipe the upper up over the edge of the last while said upper is still held taut with the hand pincers, and then presses the pulled-over portion firmly down upon the inner-sole as he releases the pincers and prepares to drive the fastening tack to hold the upper to the inner-sole. With this object in view I have in the form of these last supporting and wiping and pressing devices herein shown, provided a supporting member, corresponding to the workman's hand, to engage the under side of the last and sustain it, and wiping and pressing members preferably connected with said supporting member, and corresponding to the workman's thumb. Means is provided for moving the said last supporting and wiping and pressing devices into engagement with the shoe, and the wiping and pressing members are preferably connected with the supporting member in such manner that they are actuated by said supporting member after the latter comes into engagement with the shoe.

Mechanisms were employed in the machine of my prior Letters Patent, No. 663,777, before mentioned, for holding and inserting two fastenings, shown as tacks, at each side of the last for securing to the inner-sole the portions of upper pulled over by the grippers. These mechanisms in the

machine of my present invention are arranged to insert the two tacks spaced a considerable distance apart, preferably about an inch apart, at each side of the last. It is desirable that these securing tacks be driven into the last each the same distance from its edge. Different styles of lasts vary so much in shape that a tack presenting and inserting mechanism which is properly positioned for one style of last will, on a different style of last, insert one of the tacks farther from the edge than the other. To overcome this difficulty and render the tack presenting and inserting mechanisms self-adjusting to the edges of differently shaped lasts I have, in my present invention, so mounted the tack carrier block and the drivers that they may be automatically placed in proper position for inserting the two tacks at the same distance from the edge of the last or each a predetermined distance from the edge of the last. I have also arranged the tack inserting mechanism so as to drive the securing tacks in a direction inclined inwardly from the edge of the last, whereby the upper is pulled more closely into place by the ingoing tacks, and also the danger of splitting the last by the tacks is reduced, and the danger of driving the tack through a last having a thin edge is obviated.

These and other features of my invention, including certain details of construction and combinations of parts, will be hereinafter described and will be pointed out in the claims.

Throughout the specification and claims I have used the term "shoe" and sometimes the term "last" to designate the last with the upper, lining, counter, and inner-sole assembled thereon.

Figure 1 of the accompanying drawings is a left-hand side elevation of the head of a pulling-over machine embodying the invention. Fig. 2 is a front elevation. Fig. 3 is a vertical section of the machine. Fig. 4 is a right-hand side elevation of the lower portion of the head of the machine, certain parts being broken away. Fig. 5 is a sectional view on the line 5—5 of Fig. 4. Fig. 6 is a perspective view of the mechanism for operating the sole-rest and the heel-rest. Fig. 7 is a side elevation of the mechanism for actuating the heel-rest. Fig. 8 is a view similar to Fig. 7, the parts being in different relative positions. Fig. 9 is a side elevation of the mechanism for actuating the sole-rest, certain of the parts being broken away. Fig. 10 is a front elevation of the heel-rest. Fig. 11 is a sectional view on the line 11—11 of Figs. 9 and 10. Fig. 12 is a view similar to Fig. 9 showing the mechanism at a different stage of its operation. Fig. 13 is a sectional view on the line 13—13 of Fig. 9. Fig. 14 is a vertical, lon-

gitudinal section through the sole-rest mechanism. Fig. 15 is a section on the dotted line 15—15 of Fig. 14. Fig. 16 is a detailed view illustrating the effect of moving the grippers outwardly while pulling the upper. Figs. 17, 18, 19, and 20 are detailed views of the mechanism for manually operating the sole-rest and heel-rest. Fig. 21 is a perspective view of the mechanism for spreading the grippers. Fig. 22 is a plan view of a portion of the gripper spreading mechanism shown in Fig. 21, as seen from the dotted line 22—22 of Fig. 23. Fig. 23 is a sectional view of said mechanism, illustrating the means for adjusting the spreader. Fig. 24 is a view similar to Fig. 23 showing the adjusting devices in the position they assume when the spreading mechanism is being adjusted. Fig. 25 is a plan view of the arms for holding the combined mechanisms for supporting the last and wiping and pressing the upper in place upon the inner-sole, together with the mechanism for actuating said arms. Fig. 26 is a side elevation on an enlarged scale of the arm 20^x shown in Figs. 3 and 25 and the last supporting and upper wiping and pressing mechanism carried by said arm. Fig. 27 is a sectional view of said mechanism on the line 27—27 of Fig. 26. Fig. 27^a is a perspective view of a carrier 424 which will be described. Fig. 28 is a view similar to Fig. 27 showing the mechanism when the last support and the wiper are engaging the shoe. Fig. 29 is a view similar to Fig. 28 showing the mechanism when the last support, the wiper and the presser are all engaging the shoe and are holding the upper after the grippers have released it preparatory to the insertion of the securing tacks or other fasteners. Fig. 30 is a plan view of the mechanism shown in Fig. 29. Fig. 31 is a plan view of the mechanism for spreading the arms which carry the fastener presenting and inserting mechanisms. Fig. 32 is a front elevation of one of the fastener presenting and inserting mechanisms and the supporting arm therefor. Fig. 33 is a cross-sectional view on the dotted line 33—33 of Fig. 32. Fig. 34 is a perspective view of the swivel block for supporting the tack carrier. Fig. 35 is a perspective view of the tack carrier. Fig. 36 is a side elevation of the fastener presenting and inserting mechanism. Fig. 37 is a vertical section through the fastener presenting and inserting mechanism and through the mechanism for supporting the last and wiping and pressing the upper into position to be secured to the inner-sole. Fig. 38 is a sectional view on the dotted line 38—38 of Fig. 37. Fig. 39 is a cross-sectional view on the dotted line 39—39 of Fig. 37. Fig. 40 is a view similar to Fig. 39, but showing the fastener presenting and inserting mechanism as turned axi-

130

ally in its supporting arm for the purpose of alining it with the edge of the last so that the fasteners shall be inserted both the same distance from the edge of the last. Fig. 41 is a cross-sectional view on the dotted line 41—41 of Fig. 37, and shows the engagement of the shoulders on the fastener holding and inserting mechanism and on the last supporting and upper wiping and pressing mechanism, which shoulders coöperate for turning the swiveled fastener holding and inserting mechanism into alinement with the edge of the last. Fig. 42 is a vertical section through one of the tack holders and shows the position of the parts of the holder before the tack is driven. Fig. 43 is a similar view showing the position of the parts of the tack holder while the tack is being driven. Fig. 44 is a horizontal section on the dotted line 44—44 of Figs. 42 and 37.

The working members of the machine are supported by a head B which is provided with a depending stem 12^x vertically adjustable in a column or base A. The shoe is prepared for the machine by applying to the last the upper with its lining, the heel-stiffener, and the toe-cap, the upper being sometimes secured to the heel end of the last by a tack, and by placing the inner-sole on the bottom of the last within the upstanding marginal portion of the upper. The shoe thus assembled is presented by the workman bottom upward against a sole-rest, hereinafter described, with the upper inserted between the open jaws of the grippers at the toe and at the sides of the shoe. When the machine is started the grippers are closed to grasp the upper and then rise to pull it about the last, and a heel-rest 4 is moved yieldingly forward into supporting contact with the heel end of the shoe. The shoe is then sustained by the heel-rest, the grippers, and the sole-rest during the further operations of the machine, and does not require to be supported by the workman.

The mechanism for moving the heel-rest 4 yieldingly forward as described comprises a cam block E, mounted on the main shaft 50 D and provided with a cam groove 6, as shown in Figs. 1, 6, 7, and 8. A slide 10 is mounted to travel longitudinally in a bracket b' secured to the head B. The slide 10 is provided with a stud 8 standing in the cam groove 6, by means of which it is moved backwardly and forwardly once in each complete operation of the machine. The slide 10 is bored longitudinally to provide a chamber in which is mounted a plunger 12, see Figs. 5 and 8. The plunger is surrounded by the spring 14 which acts against collars 16 and 17 slidably mounted on the plunger. The collar 16 is confined on the rear end of the plunger by a nut 19, while the collar 17 abuts against a shoulder

at the enlarged front end of the plunger, see Fig. 8. The collars have flanges 16^a and 17^a which are adapted to engage the slide 10 at the reduced end portions 10^a and 10^b of the chamber in said slide. When the slide 10 is moved to the left, viewing Fig. 8, for actuating the heel-rest the portion 10^b thereof acts on the collar 17, which in turn acts through the spring 14 on the collar 16 and the nut 19 of the plunger to move the plunger to the left. When the slide is moved to the right for withdrawing the heel-rest the portion 10^a thereof acts on the collar 16 which in turn acts through the spring 14 on the collar 17 and the shoulder 12^a on the plunger to move the plunger to the right. The spring 14 thereby causes the movement of the plunger to be yieldingly effected in either direction for moving the heel-rest forwardly and backwardly.

The forward end of the plunger 12 is provided with rack-teeth which engage with a pinion 18 secured upon a shaft 20 mounted in bearings in the frame B, see Figs. 6 and 8. The shaft 20 is provided upon its opposite ends with gears 22, 22, which in turn engage pinions 24, 26 which are formed as sleeves mounted loosely upon a shaft 30, see Fig. 13. The pinions 24, 26 also engage rack-teeth formed upon slides 32, 34. The slides 32, 34 have in their lower faces undercut grooves which receive T-shaped ribs 36, 38 of a block 40 upon which the heel-rest 4 is supported, see Figs. 7 and 10.

The block 40 is adapted to be adjusted longitudinally of the slides 32, 34 to adapt the heel-rest for shoes of different lengths. For the purpose of securing it in adjusted position the block is provided with spring-pressed plungers 42 having on their ends pins or lugs which are adapted to be received in any one of a series of recesses 44 in the upper walls of the undercut grooves of the slides 32, 34. A shaft 46 extends transversely with relation to the plungers 42 and is provided with gear-teeth adapted to engage with rack-teeth on the plungers 42. The shaft is provided with an operating handle 48 by means of which it may be turned to depress the spring-pressed plungers and permit the block 40 with its attached heel-rest to be moved backwardly or forwardly in the slides. The block 40 is chambered out on its lower side to receive two small blocks 50, see Fig. 7, which are secured in place by pivot pins 52 that extend from front to rear. The blocks 50 are permitted to have free, pivotal movement on the pins 52 and are provided with transverse pivot pins 54 upon which are mounted depending arms 56. The arms 56 have shoulders formed on either side of their pivot pins 54 and these shoulders serve to limit the amount of pivotal movement which the arms may have about said pins 54.

Spring-pressed plungers 58 are mounted in the shoulders back of the pins and bear against the blocks 50 in such manner as to hold the arms 56 normally swung forward.

- 5 On the lower ends of the arms 56 are formed forwardly extending trunnions 60 which are secured in bearings formed on the rear side of the heel-rest 4. By this arrangement the heel-rest is permitted to have 10 free, swinging, lateral movement upon the trunnions 60 and the pivot pins 52, this movement being in a direction transverse of the length of the shoe. The heel-rest is also permitted to have a limited rocking movement about the pivot pins 54 in a direction 15 longitudinal of the shoe.

The block 40 is provided with a depending portion having on its front face a corrugated or roughened surface 64. The arms 20 56 which carry the heel-rest support a corrugated plate or link 66 located opposite the corrugated surface 64 on the block 40 and adapted to engage said surface 64 when the heel-rest is swung backwardly about the 25 pivot pins 54 and by such engagement to lock the heel-rest against lateral movement. The spring-pressed plungers 58 normally hold the heel-rest swung forwardly and the plate 66 out of engagement with the surface 30 64, as shown in Fig. 7.

The heel-rest is formed on its front side with converging faces, as shown in Fig. 11, to engage the sides of the heel end of the shoe when the heel-rest is moved forwardly by 35 the mechanism above described, the recess or angle between the converging side faces receiving the usual shoe assembling tack which projects from the middle of the heel end.

It will be understood that the shoe is held 40 by the workman against the sole-rest with the fore-part in such position as to cause the upstanding edge portions of the upper at the toe and sides of the shoe to stand within the open jaws of the grippers.

45 As is well known, right and left lasts vary in shape in such a way that when the fore-part is positioned properly, centrally of the machine, for the grippers to engage the upper the heel of a right last will be at one 50 side of the median line of the machine and the heel of the left last will be at the other side of the median line. Lasts of different styles vary in this respect in different degrees. It is necessary, therefore, to arrange 55 the heel-rest so that it may be adjusted laterally according to the different positions occupied by the heels of different lasts. The heel-rest occupies a retracted, inoperative position when the machine is at rest and by 60 means of the construction above described it is moved yieldingly forward from its inoperative position until it comes into contact with the heel end of the shoe. As said heel-rest meets the shoe, if the heel end 65 thereof is not directly in front of the heel-

rest, one of the side walls of the rest engages one side of the heel before the other wall engages the heel, and, in the continued forward movement of the heel-rest, said rest is automatically shifted laterally by the shoe 70 swinging on the pivot pins 52, so that when it comes fully into engagement with the heel it will have positioned itself laterally so as to be directly in the rear of the heel end of the shoe. In the further forward movement of the heel-rest, yieldingly effected as above described, the rest is rocked rearwardly on its pivot pins 54, as shown in Fig. 8, against the action of the spring-pressed plungers 58, and the corrugated 75 plate 66 is brought into engagement with the corrugated surface 64 of the block 40, so that said heel-rest is locked thereby against any lateral movement so long as said rest remains in supporting engagement with the shoe being operated upon. 80

The spring 14 surrounding the plunger 12, and by means of which the movement of said plunger is yieldingly effected, permits the heel-rest 4 to come to rest after being 90 moved into firm engagement with the shoe, but preferably without moving the last any, said spring being compressed during the remaining portion of the movement of the slide 10. The heel-rest is thus arranged for 95 supporting shoes differing somewhat in length without the necessity of adjustment. For accommodating shoes varying greatly in length the heel-rest may be adjusted in the slides 32, 34. 100

It is desirable in most classes of work to lock the heel-rest positively against rearward movement while the upper is being drawn over the bottom of the last and secured to the inner-sole. It is also desirable 105 in many classes of work to give the last a slight positive forward movement at the end of the pulling movement of the grippers in stretching the upper about the last. The purpose of this movement of the last in the 110 pulled upper is to effect what is known in the art as the "setting" of the shoe, that is, the final conforming of the upper to the shape of the last.

For effecting the locking of the heel-rest 115 against rearward movement and the positive forward movement of the heel-rest for setting the shoe, when this forward movement is required, the slide 10, before described, is provided at its forward extremity 120 with a block 70 having at its front end an inclined face 68 adapted to engage with the rear end of a lever 72, see Figs. 6, 7, and 8, during the last portion of the rearward movement of the slide 10, it being understood 125 that it is the rearward movement of the slide 10 which advances the heel-rest and that said rest is retracted toward inoperative position during the forward movement of the slide 10. The lever 72 is pivoted at 130

74 to a portion of the head B, see Fig. 6, and its forward end is provided with a pawl 76 held by a spring-pressed plunger 78 normally in engagement with a ratchet wheel 80. The ratchet wheel is formed upon or secured to the sleeve shaft on which is formed the pinion 24 before mentioned, see Figs. 6, 7, and 13. The movement of said lever 72 and the pawl 76 is communicated to the heel-rest through said pinion 24 directly to the slide 32, and indirectly through the gears 22, 22 on the shaft 20 and the pinion 26 to the slide 34, and of course by said slides 32 and 34 the movement is communicated to the heel-rest through the mechanism heretofore described.

The portion of the oscillation of the lever 72 during which the pawl 76 is permitted to engage the ratchet wheel 80 is determined by a pawl controller 82, shown as a hooked lug formed on a plate 84 which is adjustably secured to the head B by a bolt 86, as shown in Fig. 7. The lever 72, carrying the pawl 76, is acted upon by a spring-pressed plunger 88 which normally holds that end of the lever which carries the pawl raised and the other or rear end of the lever in contact with the block 70. While the rear end of the lever is on the plane face 30 of the block 70 the pawl controller 82 embraces the upper arm 77 of the pawl 76 and holds the acting end of said pawl out of contact with the ratchet wheel 80. When the lever 72 is acted upon by the inclined face 68 of the block 70 to move the pawl downwardly the pawl controller 82 keeps said pawl away from the ratchet 80 until the arm 77 of the pawl has been carried below said pawl controller, after which the pawl engages the ratchet and locks said ratchet against rearward movement. If the adjustment of the pawl controller 82 is such that this engagement takes place during the oscillation of the lever 72, the ratchet wheel is first turned to move the heel-rest positively forward, and then locked, as explained, against backward movement. By adjusting the pawl controller 82 up or down the portion of the stroke of the lever 72 during which the pawl will be allowed to engage the ratchet may be varied so that the heel-rest will be merely locked or be moved forward a greater or less distance, according to the position of the controller. It will be understood that this movement of the heel-rest is positively effected and advances the last, while the movement imparted by the plunger 12 is yieldingly effected and merely moves the heel-rest into supporting engagement with the shoe. The lug may, of course, be so adjusted as to hold the pawl at all times out of engagement with the ratchet and so discontinue the locking and the positive forward movement of the heel-rest.

It is sometimes desirable to give the heel-rest a forward movement in addition to and independent of the above-described movements which are imparted to it automatically in the regular operation of the machine. For this purpose means is provided for connecting the ratchet wheel 80 with a hand lever 160 which depends from a hub 90 on the shaft 30 (see Figs. 6, 12, 19, and 20). The hub 90 has a bore parallel with the shaft 30 to receive a rod 91 having at its ends eccentric portions 92 and 94 (see Figs. 17 and 18). The eccentric portion 94 is positioned adjacent to the periphery of the ratchet wheel 80 and constitutes a form of pawl to engage said ratchet wheel at times. The eccentric portion 92 on the rod stands just without the outer face of the hub 90 and is acted upon by a cam face 96 of a device 162, herein termed the "pawl-disengaging device," which is pivotally connected at 165 to the hub 90 and is provided at 166 with a finger-piece by means of which it may be moved against the action of spring-pressed plungers 168, 170 (see Fig. 9). The eccentric portion 92 of the rod 91 is acted upon by a spring-pressed plunger 98 which, when permitted to do so, turns said rod for putting the eccentric portion 94 into engagement with the ratchet wheel 80, as shown in Fig. 17. The cam face 96 of the pawl-disengaging device normally holds the rod 91 with its pawl 94 out of contact with the ratchet wheel 80, but when said disengaging device is turned into the position shown in Fig. 20 the cam face 96 is moved out of contact with the eccentric portion 92 of said rod and the spring-pressed plunger 98 is permitted to turn said rod about its own axis for moving its pawl 94 into engagement with the ratchet wheel 80. By this means the hand lever 160 may be connected with the ratchet wheel 80 of the heel-rest actuating mechanism so that said heel-rest may be manually advanced. The pawl 76 acts at such times as a locking means to hold the ratchet 80 against rearward movement, thus securing the heel-rest in the position to which it may be moved.

The shoe-bottom-rest, or "sole-rest," as it is herein called, is mounted slidably in a carrier 120 which is pivotally supported on the shaft 30, heretofore described, see Figs. 3, 13, and 14. The sole-rest comprises a shank 118 having arms 124, 124 which extend obliquely forward to engage the inner-sole near its edge and an arm 126 which extends directly forward toward the toe of the inner-sole, see Fig. 15. The arm 126 has an adjustable footpiece 127 pivoted to it at 128 and acted upon by a spring-pressed plunger 130. The foot-piece is provided with a stop-screw 132 for adjusting it about its pivot to vary the vertical position of its

acting end with relation to the arm 126. By this adjustment the sole-rest may be adapted to engage properly lasts the bottom faces of which have different degrees of longitudinal curvature. The arm 126 is adjustably mounted in a channel in the shank 118 of the sole-rest. The arm is provided with ratchet-teeth which are adapted to be engaged by a spring-pressed pawl 129 mounted in one side of the shank 118, as shown in Fig. 15. The feet of the several arms of the sole-rest are roughened so as to engage the inner-sole frictionally and prevent the rest slipping with relation to it. This insures that the inner-sole shall be moved with the rest in the forward and backward movements which are imparted to said rest during the operation of the machine, as will be described.

10 The sole-rest is moved longitudinally of the last automatically during the regular operation of the machine and may also be moved manually when the machine is at rest.

15 The automatic movements of the sole-rest longitudinally of the last are imparted by the slide 10 heretofore described, which in turn is actuated by the stud 8 standing in the groove 6 in the cam block E. The slide 10 has a laterally and forwardly extending arm 140 (see Figs. 6 and 9), the extremity of which is formed to constitute a split clamp 142 for holding the stud 144 of a block 146. The block is provided with a longitudinal 20 groove 148 in which is fitted a slide-block 150. A lever 152 is fulcrumed on a fixed stud 154 which extends from a bracket b^2 secured to the rigid head B, see Fig. 1. Said lever has one end connected to the slide-block 150 and at its other end pivotally supports a device 156, herein called a "pawl." By this arrangement when the slide 10 is moved rearwardly or to the left in Figs. 1 and 12, as it is during the first part 25 of each operation of the machine, the lever 152 is rocked to draw the pawl 156 upwardly or to force it downwardly, according to the adjustment of the block 146. If the block 146 is adjusted as it is in Figs. 1 and 12, which show the respective positions of the parts at the beginning and at the end of a rearward movement of the slide 10 and block 146, the lever 152 will be rocked to draw the pawl 156 upwardly. If, however, the block 146 is adjusted as it is in Figs. 6 and 9 the lever 152 will be rocked to force the pawl downwardly. The pawl 156 is provided on its front face with an aperture or socket 158 adapted to receive a stud 30 or lug 172 on the hub 90 of the hand lever 160 before described. A spring-pressed plunger mounted in the lever 152 bears against the pawl 156 and tends to maintain it in engagement with the hub 90. The hub 35 is fast on the shaft 30 that has secured to it or formed integral therewith a pinion 174 which engages rack-teeth on the shank 118 of the sole-rest, (see Figs. 6, 13, and 14). It will now be understood that when the block 146 is adjusted as in Figs. 1 and 12 the lever 152 will operate during the movement of the slide 10 to the left to turn the shaft 30 in the direction indicated by the arrow thereon in Fig. 12 and draw the sole-rest rearwardly, and, through the engagement of said sole-rest with the inner-sole, draw the inner-sole rearwardly. If, however, the block 146 is adjusted as shown in Figs. 6 and 9 the lever 152 will be rocked during the movement of the slide 10 to the left, to force the pawl 156 downwardly and so rotate the shaft 30 in the direction of the arrow thereon in Fig. 9 to force the sole-rest and the inner-sole forwardly. The block 146 may be adjusted in the clamp 142 so that its groove will be at any desired angle with the vertical, whereby to vary the extent of the forward or backward movement which will be imparted to the sole-rest, or it can be so adjusted that the groove will occupy a horizontal position so that the lever will not be rocked at all, and the movements of the sole-rest longitudinally of the last will be discontinued. Such is the mechanism for imparting to the sole-rest its automatic movements for moving the inner sole forwardly or backwardly during the regular operations of the machine. For the purpose of enabling the workman to operate the sole-rest manually for moving the inner-sole forwardly or backwardly the pawl 156, which together with the stud 172 constitutes a locking means for normally preventing any movement of the sole-rest other than that imparted to it by the automatic mechanism, may be disconnected from the hub 90 of the hand lever 160, thus leaving said lever free to be turned in either direction.

40 For disconnecting the pawl 156 from the hub 90 the pawl-disengaging device 162 has a cam 167 (Figs. 19 and 20) adapted to be moved into contact with the pawl 156 for disengaging said pawl from the stud 172 of the hub 90. The pawl-disengaging device is normally held in the position shown in Fig. 9 by two spring-pressed plungers 168 and 170. The spring actuating the plunger 170 is considerably stronger than the spring actuating the plunger 168 so that the disengaging device may be moved into its first position, shown in Fig. 19, by depressing the spring plunger 168 and will then come to rest against the plunger 170, unless a materially greater force is applied, whereupon the plunger 170 will yield and permit the pawl-disengaging device to be moved into its second position.

45 The cam face 167 is of considerable length so that when the pawl-disengaging device is depressed into its first position the pawl 156

will be disengaged from the stud 172, and when said disengaging device is moved farther into its second position by depressing the plunger 170, as shown in Fig. 20, the pawl 156 will be still held out of engagement with the stud 172. The disengaging device is moved at times into its second position, shown in Fig. 20, for carrying the cam face 96 out of the way of the eccentric portion 92 of the rod 91 and permitting the rod 91 to be actuated by its spring plunger 98 for connecting the hand operated lever with the heel-rest actuating ratchet 80, as before described. When the pawl-disengaging device is in its second position the sole-rest and heel-rest are both operatively connected with the hand operated lever and may be actuated thereby.

A returning spring *s* is mounted in the sole-rest carrier 120 and is adapted to be engaged at each end by a lug on the shank 118 of the sole-rest and be compressed thereby when the sole-rest is moved in either direction. This spring serves to return the sole-rest and the hand lever to normal central position when the hand lever has been released after the sole-rest has been operated by the lever. This insures that the stud 172 will be returned to position to be properly engaged by the pawl 156 at the next operation of the machine.

As before stated, the sole-rest carrier 120 is pivotally mounted to turn about the shaft 30. The carrier 120 has an upwardly extending arm which is provided with a cam roll 368^x adapted to be engaged by a face cam 378^x on the end of the main shaft D. A spring *x* is mounted in a socket in the head B and bears against the rear end of the carrier 120 to hold the roll in position to be actuated by the cam 378^x. The carrier is rocked forwardly by the cam against the influence of the spring, for depressing the sole-rest, and thereby depressing or sinking the last into the pulled upper. This sinking of the last into the upper takes place at approximately the end of the upward movement of the grippers for pulling the upper. Preferably the parts are so timed that the said movement of the sole rest is completed before the heel rest is advanced by the mechanism, heretofore described, far enough to interfere with the downward and backward movement of the shoe. An adjustable stop *x'*, co-operating with a stop *x''* on the head B, as shown in Fig. 3, controls the position of the roll 368^x relative to the cam 378^x and so determines the amount of rocking movement imparted to the sole-rest carrier.

The means for engaging and pulling the upper comprises a toe gripper mechanism and two side gripper mechanisms, one for each side of the shoe. The said gripper mechanisms are operated from cams 188^x

and X³⁰ mounted on the main driving shaft D. The cam 188^x operates through a connecting-plate 172^x to actuate a lever *e*^x which is fulcrumed on a rod 152^x secured in the machine head B. The lever *e*^x supports 70 the toe gripper mechanism.

The connection between the plate 172^x and the lever *e*^x is a yielding one for effecting yieldingly the upward movements of the toe gripper mechanism. To this end the connecting plate 172^x is provided with a stem 170^x upon which is slidably mounted a block 180^x acted upon by a spring 176^x which surrounds the upper portion of the stem 170^x and the tension of which is regulated by a nut 174^x. The lever *e*^x is pivotally connected at its rear end with the block 180^x. This arrangement is such that when the cam 188^x operates to pull down the rear end of the lever *e*^x this movement is yieldingly transmitted to the lever through the spring 176^x. The stem 170^x is provided with a fixed flange 184^x which constitutes a rest for the lower side of the block 180^x. When the cam 188^x operates for lifting the 90 rear end of the lever *e*^x for depressing the grippers the movement of the grippers is positively effected through the fixed flange 184^x. Said stem 170^x is adjustably connected to the connecting-plate 172^x so as to allow of varying the height of the fixed flange 184^x and so varying the lowermost position to which the toe gripper mechanism will be moved.

The toe gripper mechanism, which is pivotally supported near the front end of the lever *e*^x, comprises a single pair of grippers which are preferably constructed and operated as described in said application for Letters Patent, Serial No. 532,681, originally filed January 31, 1903.

The cam X³⁰, before mentioned, operates through a connecting-plate 134^x to actuate two levers 154^x, 154^x that are pivoted on the aforesaid rod 152^x and which support near their front ends the two side gripper mechanisms. The connection between the connecting-plate 134^x and the levers 154^x is similar to the connection above described between the connecting-plate 172^x and the lever *e*^x so as to effect yieldingly the downward movement of the rear end of said levers for lifting the side gripper mechanism to pull the upper. To this end the plate 134^x is provided with two stems 138^x, 138^x, one of which is shown in side elevation in Fig. 1 and the other in Fig. 3, and each of which carries a block 148^x acted upon by the lower end of a spring 150^x, the tension of which is regulated by an adjusting nut 142^x. The levers 154^x are pivotally connected to the blocks 148^x, and as said blocks are free to slide on the stems 138^x the downward movement of the rear ends of the levers is effected through the springs 150^x when the 13

cam is actuated for pulling down the connecting-plate 134^x. The stems 138^x are provided with fixed flanges 147^x upon which the blocks 148^x rest, so that when the connecting-plate 134^x is moved upwardly by the cam, the upward movement of the rear ends of the levers for moving the side grippers downwardly is positively effected. The stems 138^x are adjustably connected to the plate 134^x to permit of varying the lowermost position to which the side grippers may be moved.

The levers 6^x, and 154^x, 154^x are extended forwardly beyond the points where the grippers are connected to constitute handles by means of which the grippers may be depressed manually, the springs 176^x and 150^x at such time yielding to permit the required movement of the levers.

20 The provision of independent yielding connections between the gripper operating levers 154^x and their actuating cam X³⁰ not only insures that each of the side gripper mechanisms will be actuated yieldingly for gripping and pulling the upper, but also permits either one or both of the side gripper mechanisms to be depressed by means of the handles of the levers 154^x for slackening the tension on the pulled upper. The tension of the 30 springs 150^x is so regulated that the blocks 148^x will move upwardly on the stems 138^x, compressing the springs somewhat during the pulling operation. This insures that when either of the side gripper mechanisms 35 is manually depressed for slackening the tension on one side of the upper, the spring 150^x, acting on the lever of the other gripper mechanism, will immediately expand to take up this slack, thereby shifting the upper transversely about the last.

40 The side gripper mechanisms are preferably constructed and operated as shown and described in my pending application Serial No. 200,342, filed March 28, 1904, which is 45 a division from this application.

It will be understood that after the grippers have pulled the upper and before they release it they are moved inwardly over the last, toward each other, to draw the pulled upper over the inner-sole in position to be fastened. This inward movement of the grippers is yieldingly effected by springs 316^x, see Figs. 2 and 3, mounted in chambers in the portions b³ of the frame B 50 through which the grippers are guided. There are two of these springs for each gripper mechanism and they are arranged with their inner ends resting against the ends of plates 316^{xx}, see Fig. 2, which in 55 turn bear against the gripper operating bars. The springs are backed up and their tension is adjusted by stop-screws 316^z. After the upper has been secured to the inner-sole the grippers are spread apart again to 60 their initial positions for engaging the up-

per of the next shoe presented to the machine. The outward movement of the grippers to their initial positions is effected positively by suitably actuated spreading mechanism which is retracted automatically at 70 the proper time in the operation of the machine for allowing the springs to move the grippers inwardly.

It is necessary to adjust the spreading mechanism so that it will spread the grippers more or less for putting them in different initial positions for grasping the uppers of shoes of different sizes. Pulling-over machines as heretofore constructed have been provided with means for varying the initial positions of the grippers by adjusting the actuator for the spreading mechanism so as to vary the stroke of said mechanism, the extent of the stroke varying with the size of the shoe being operated 80 upon. This arrangement has proved not to be entirely satisfactory because approximately the same amount of inward movement of the grippers for overdrawing the upper is required for a small shoe as for a 85 large one. I have, therefore, provided improved means for adjusting the position of the spreading mechanism with relation to its actuator whereby the stroke of the spreading mechanism and therefore the inward and outward swing of the grippers 90 remains uniform in extent, but takes place 95 between different limits.

By my improved arrangement the actuator has always a uniform stroke and im- 100 parts to the spreader a uniform stroke whatever initial position said spreader may be caused to assume.

The spreading mechanism is not claimed in this application as it is claimed in said 105 divisional application Serial No. 200,342, filed March 28, 1904, but it is herein described and shown for the purpose of presenting in this application a more complete description of the machine as a whole.

The mechanism above referred to for spreading the grippers apart after they have been moved inwardly by the springs and for holding them apart during the up-draw movement of the grippers comprises 115 a lever 802^x mounted on a pin 800^x in the head B, see Figs. 4 and 5. The lever has one end 816^x in position to be actuated by the groove 804^x in the cam block E before mentioned. The upper end of the lever 802^x 120 is provided with a toothed rack 808^x which meshes with a pinion 810^x on a shaft 812^x mounted in the machine head B. The shaft 812^x is provided with gear-teeth 822^x adapted to engage rack-teeth formed on a reduced 125 portion of a bar 818^x, which is slidably mounted in a part 814^x shown in Figs. 3 and 5 and hereinafter described. The bar 818^x has a depending lug 840^x adapted to engage a co-operating lug 826^x standing up 130

from a slide bar 327, herein called the "actuator" for the spreading mechanism. The slide bar 327 is provided on its lower face with rack-teeth which actuate a pinion 5 fast on a shaft 330, see Figs. 3, and 21 to 24 inclusive. The shaft 330 is surrounded by a sleeve shaft 332 to which it is connected by a clutch. The clutch comprises a segmental rack-plate 334 (see Fig. 24) secured to a 10 flange 336 on the sleeve shaft, and rack-teeth formed on the adjacent side of a flange 338 formed on the end of the interior shaft 330. The flange 336 on the sleeve shaft is cup-shaped so as to inclose the flange 338 15 and protect the interior shaft from accidental displacement. The sleeve shaft is 20 acted upon by a spring 340 to press it normally outward and hold the rack-teeth on the segment 334 in engagement with the 25 rack-teeth on the flange 338.

The sleeve shaft 332 is provided with gear-teeth 342 which engage rack-teeth formed on the lower side of a sliding bar 344. The sliding bar 344 supports a wedge-shaped head 346 for spreading the side gripper mechanisms apart and said bar has 30 projecting forwardly from it an arm 348 provided with a roller 226 to engage the operating bar 68^x of the toe gripper mechanism. Between the inclined sides of the wedge-shaped spreader block 346 and the side gripper operating bars 68^x are interposed blocks 350 connected by vertical pivots 352 to the machine head B, and provided 35 with anti-friction rollers 333 for engaging the inclined sides of the spreader block 346. The blocks 350 are bored to receive for rotative movement therein stems 354 having pivotally connected to their outer ends contact plates 356 for engaging with the operating bars 68^x of the side gripper mechanisms. The contact plates 356 are supported on pivots extending vertically at right 40 angles to the axis about which the stems 354 turn. This permits the contact plates 356 to have movement in all directions in order that they may maintain complete contact with the operating bars 68^x in the various 45 positions to which said bars 68^x are moved.

The mechanism above described will operate to hold the grippers normally spread apart, as described, until, in the operation of the machine, they have stretched the upper about the last. Thereupon the shaft 50 812^x is actuated for retracting the slide bar 818^x and permitting the spreader mechanism to be moved rearwardly for allowing the several gripper mechanisms to be moved toward the middle of the last.

For adjusting the spreading mechanism to cause the grippers to assume different initial positions the sleeve shaft 332 above referred to may be unclutched from the interior shaft 330 by moving it inwardly, 55 lengthwise of said shaft, against the action

of the spring 340. The sleeve shaft may then be rotated in either direction and in so doing it will, through the gear-teeth 342 and the rack-teeth on the bar 344, adjust said bar 344 for causing the side grippers to be spread apart more or less and the toe gripper mechanism to be moved toward or away from the side gripper mechanisms. After the desired adjustment has been made the spring 340 will automatically move the sleeve shaft outwardly to cause it to become clutched to the interior shaft and thereafter, in the operation of the machine, the spreading mechanism will be actuated to move the grippers always back to their new initial positions.

364 indicates a spring bearing at one end against a lug depending from the bar 344 and at its other end against the actuating bar 327 to keep said actuating bar always forced to the left, with its lug 826^x against the lug 840^x on the slide 818^x.

It is sometimes desirable to adjust the side gripper mechanisms toward or from each other without adjusting the toe gripper mechanism, as, for instance, for shoes varying considerably in width and but slightly or not at all in length. For this purpose the wedge block 346 is adjustably mounted on the sliding bar 344 of the spreader. The wedge block is provided on its lower side with a lug 360 in which works a screw bolt 362, the rear end of which abuts against a lug depending from the sliding bar 344. By turning the screw bolt 362 to move it backwardly the wedge block 346 is adjusted forwardly for spreading the side gripper mechanisms farther apart. By turning the screw bolt in the opposite direction the wedge block is permitted to be moved rearwardly by the pressure of the side gripper mechanisms against its inclined faces.

The portions of the operating bars 68^x of the gripper mechanisms which are engaged by the contact plates 356 and the contact roller 226 of the spreading mechanism are provided with inclined faces shown at 222 in Figs. 3 and 21, for the purpose of causing the grippers to be moved outwardly somewhat while they are being raised to pull the upper. By this means the marginal portions of the upper are carried away from the edge of the last as the upper is being pulled so that the inner-sole is not lifted by the contact of the upper with the edges of the inner-sole. This feature of the invention is not claimed herein as it is claimed in said divisional application Serial No. 200,342.

Mechanism is also provided by which the side grippers may be moved forwardly and backwardly for shifting the upper longitudinally of the last. This mechanism comprises a shaft 258^x provided with a hand lever 292^x, as shown in Figs. 1, 2, 3, and 4. The shaft has a pinion 260^x in engagement

with a rack-bar 256^x, see Fig. 3. The rack-bar is provided with a transverse guideway in which is mounted a guide-block 254^x having a portion received in a guideway 240^x formed in the side of one of the grippers carriers 161 of the right-hand side gripper mechanism, see Fig. 3. The shaft 258^x also has a pinion 266^x in engagement with a rack-bar 250^x having a transverse guideway 10 in which is mounted a guide-block 248^x having a portion received in a guideway 240^x in one of the grippers carriers of the left-hand side gripper mechanism, as shown in Fig. 1. The rack-bar 256^x, having a connection with the right-hand side gripper mechanism, engages the upper side of its pinion 260^x, while the rack-bar 250^x for the left-hand side grippers engages the lower side of its pinion 260^x, whereby said rack-bars and the side gripper-mechanisms connected to them are moved in opposite directions by the rotation of the shaft 258^x. By this means the side gripper mechanisms may be swung simultaneously one forwardly and the other backwardly to adjust 25 the upper in a direction longitudinal of the last.

The hand lever 292^x has pivotally connected to it a finger-piece 302^x (see Figs. 2 and 4) which has engagement with a locking pin 303^x adapted to take into a suitable notch in a fixed part of the frame for locking the shaft 258^x normally with the grippers positioned opposite each other. The finger-piece 302^x is acted upon by a spring 306^x against the resistance of which it may be depressed for withdrawing the locking bolt when it is desired to move the grippers for adjusting the upper.

40 The grippers carrier of the toe gripper mechanism has a bar 232^x extending upwardly along the front face of the operating bar 68^x and provided with a forwardly extending lug which is engaged by a lever 230^x having toothed connection with a lever 228^x pivoted to the gripper lever *e*^x. This arrangement is such that the workman, by manipulating the lever 228^x, may raise the grippers carrier relatively to the operating bar 68^x as fully described in said Letters Patent No. 663,777, and thereby cause the toe grippers to be opened for releasing the toe portion of the upper. This is desirable at times in order to allow the upper to be 55 shifted longitudinally or transversely about the last with greater freedom.

In the embodiment of my invention herein shown the devices for wiping the upper upwardly along the side of the last and then 60 pressing the overlaid upper downwardly upon the inner-sole into position to be secured thereto, and for supporting the last during the operation of securing the pulled-over upper to the inner-sole, are combined 65 in a single mechanism at each side of the

last. These mechanisms are brought into action after the upper has been pulled into place by the grippers and after the manual adjustments of the pulled-over upper have been effected, if any manual adjustments 70 are found by the workman to be necessary. The said mechanisms are supported upon arms 20^x, 22^x at each side of the last. The arms 20^x and 22^x are pivotally connected to the machine frame at 16^x and 18^x, respectively, for horizontal, swinging movement toward and from each other. The arms are formed as bell-crank levers and their rear ends are provided with segmental racks engaged by rack-bars N²⁴, N²⁸. 80 The rack-bars have rear extensions received within a sliding block N²⁶ and encircled by springs N⁴⁰, N⁴⁴. An equalizing device N⁷ is pivotally attached to the slide N²⁶ and its ends embrace the extensions of the rack-bars, abutting against the springs surrounding said extensions. The slide N²⁶ is provided with a stud N³⁴ which is acted upon by the cam face N³³ of the cam block E before mentioned, whereby said slide is moved 90 for drawing the rack bars N²⁴ and N²⁸ backwardly and thereby moving the outer ends of the arms 20^x and 22^x toward each other. The slide N²⁶ is actuated in the opposite direction by a spring N³². By means of the 95 springs N⁴⁰ and N⁴⁴ the movements of the arms 20^x and 22^x are yieldingly effected and the equalizing device N⁷ permits either arm, if it comes into engagement with the side of the last before the other arm, to come to 100 rest while the other arm continues to move. The arms are thereby permitted to adapt themselves to the position of the last. The construction and operation of the mechanism for actuating the arms 20^x and 22^x is 105 more fully shown and described in said Letters Patent No. 950,701.

The combined mechanisms for supporting the last and wiping and pressing the pulled upper into position to receive the 110 securing tacks are carried on the free ends of the arms 20^x and 22^x. These mechanisms are duplicates of each other and only one of them is therefore shown in detail. Referring to Figs. 1, 2, 3, and 26 to 30 inclusive, said mechanism comprises a last support 400 secured by a ball and socket joint to a block 402 which is mounted to slide in an inclined guideway in the lower side of the enlarged free end of the arm 20^x. 115 The block 402 is held in its forward or upper position by a spring 404 located in a chamber in the block and confined in position by a small plate or lug 406 projecting from the arm 20^x into the chamber in said block. 120 The last support 400 is preferably provided with a cushioning surface, as shown, to prevent marring or bruising the upper of the shoe. The block 402 is provided on one side with rack-teeth which are in engage- 130

ment with a pinion 408 mounted on a short shaft 410 in a recess or chamber in the enlarged end of the arm 20^x. A second block 412 is mounted in a guideway in the upper 5 side of the enlarged end of the arm 20^x and is provided with rack-teeth which are engaged by the pinion 408, whereby motion is communicated from the block 402 through the pinion 408 to the block 412. The block 10 412 moves the wiper 414 for forcing the pulled upper firmly against the edge of the last and holding it from slipping back after it is released by the grippers, and said block 412 also moves the presser 416 for 15 forcing the pulled-over portion of the upper firmly down upon the inner-sole and the edge portion of the inner-sole closely down upon the last, as shown in Fig. 29. For the purpose of supporting these parts the block 20 412 is forked at its front end to provide two branches, 418, 420, one above the other between which is mounted a carrier 424 shown separately in Fig. 27^a. The upper face of 25 the branch 420 is provided with an arc-shaped groove 422, and the carrier 424 is provided with arc-shaped guiding ribs 423 which fit in the groove 422, whereby said carrier is permitted to move horizontally in a curved path in the block 412 so that it 30 may adjust itself to the shape and position of the part of the shoe engaged by the wiper. The carrier has a recess in its lower side to form a guideway in which is located the shank 426 of the wiper 414. The 35 wiper is held yieldingly in its forward or most advanced position by a spring 428 contained in a socket in the shank of the wiper and bearing at its rear end against the wall of the block 412. The carrier 424 40 is provided with forwardly projecting lugs 430 and 432, see Fig. 30, between which is pivoted the presser 416. The presser is provided with a downwardly extending arm 434 which is received in a notch or recess 45 in the upper side of the wiper 414, whereby when the wiper, after coming into contact with the shoe, yields backwardly against the pressure of its spring, the presser is tipped on its pivot and caused to press 50 downwardly upon the pulled-over upper to force said upper firmly against the inner-sole and the inner-sole firmly down upon the sole of the last, as shown in Fig. 29. The presser is also provided with a rearwardly projecting lug or arm 436 which engages the beveled upper face 438 of the carrier 424 for limiting the pivotal movement of the presser and the outward movement of the wiper under the influence of 55 the spring 428 acting on the latter. The carrier 424 is provided with a shoulder 440 for a purpose which will be hereinafter explained, it being borne in mind that said carrier automatically adjusts itself angularly, by coming into contact with the edge 60 65

of the last, into a position approximately parallel with the edge of the last.

The arrangement of the last supporting and upper wiping and pressing mechanism is such that when the arms 20^x and 22^x are actuated to move the mechanisms toward a shoe, the upper of which has been pulled and is held in position by the grippers, the last support 400 first contacts with the side of the shoe. The movement of the arms continuing the block 402 yields backwardly against the pressure of the spring 404 and rotates the pinion 408 and moves the block 412 forwardly to bring the wiper 414 into engagement with the upper. Fig. 28 shows the relation of the several parts at this stage of the operation. As the wiper presses against the edge of the shoe and wipes the upper firmly against the last, the block 412 continues to move forwardly, the spring 428 yielding, and the presser 416 moves with said block 412. During this movement of the presser and block 412 relatively to the wiper, which has been stopped by contact with the last, the presser is rocked by engagement of its arm 434 with the notch in the wiper and the acting end of said presser is thereby forced downwardly into pressing engagement with the upper. The relation of the parts at this stage of the operation is 95 shown in Figs. 29 and 30.

The pinion 408 acts as an equalizing device so that the wiper 414 is forced against the side of the shoe and the presser 416 against the bottom of the shoe with a pressure approximately equal to the resistance of the last against the last support 400. The several devices of this mechanism are brought into engagement with the shoe successively, the last support 400 first engaging the shoe and actuating the pinion 408 which advances the wiper and the wiper in turn rocks the presser into engagement with the upper. 100

The mechanisms above described, acting 110 at the sides of the shoe, support it firmly while the tacks are being driven for securing the pulled-over upper to the inner-sole. I prefer to employ at the toe of the shoe a wiping and pressing mechanism such as is 115 shown and described in detail in said Letters Patent, No. 988,582, and only a brief description of this mechanism is here necessary. Referring to Fig. 3, 72^a indicates the abutment or edge gage secured to the lower 120 end of a swinging arm 672^x, hereinafter referred to, and 60^a indicates the combined wiper and presser which is slidingly mounted in said arm. The presser normally rests near its front end upon the upper surface of 125 the abutment and its rear end is sustained by a spring-actuated rod 74^a. The upper face of the presser near its rear end rests against a rigid block 65^a. When the arm 672^x is moved over the last, as hereinafter 130

described, the wiper and presser is brought into engagement with the shoe, the upturned, forward end of the presser riding over the edge of the shoe, causing said 5 presser to be rocked with relation to its fulcrum on the block 65^a, the spring-actuated sustaining rod 74^a yielding for this purpose and causing the presser to bear yieldingly upon the upper.

10 The means for securing the upper to the inner-sole, after it has been pulled-over by the grippers and wiped and pressed into place by the wiping and pressing mechanisms above described, comprises tack carrying and inserting mechanisms, three in number, coöperating with each of the gripper mechanisms. These mechanisms comprise arms 672^x, 674^x and 676^x pivotally sustained at their upper ends by a forwardly projecting portion *b*⁴ of the frame B. The tack driver bars are guided in these arms and are operated by mechanism which is the same as that shown in my before-mentioned Letters Patent No. 663,777. This mechanism will 15 therefore be but briefly described herein. The drivers are actuated for depressing them to insert the tacks by a torsion spring 708^x surrounding a shaft 706^x to which is rigidly secured a lever 718^x, see Fig. 3. The 20 lever 718^x rests at its forward end upon a plate 720^x having portions in engagement with each of the several drivers. The drivers are elevated against the tension of the spring 708^x and normally held in their 25 raised position by means of the part 814^x before described. This part 814^x is pivotally mounted upon the shaft 812^x (see Figs. 3, 5, and 31) and has depending from it an arm 817^x having a roller running in the groove 30 804^x of the cam block E, see Fig. 3. By this means the part 814^x is oscillated about the shaft 812^x. The part 814^x has lateral extensions at its front end in which are guided for longitudinal movement slide bars 844^x 35 and 848^x. These slide bars have portions 924^x and 926^x for engaging under coöperating shoulders 928^x and 930^x (see Figs. 4 and 31) secured to the driver bars 682^x and 694^x, respectively, of the tack inserting mechanisms which operate at the sides of the shoe. The sliding bar 818^x, which slides in the part 814^x, as before described, is provided near its front end with a shoulder 920^x adapted to engage a coöperating shoulder 50 922^x secured to the driver bar of the tack inserting mechanism which operates at the toe of the shoe (see Figs. 1, 3, and 31). When the part 814^x is rocked by the arm 817^x and cam groove 804^x to elevate the 55 front end of said part the drivers are raised and tension is developed in the spring 708^x for actuating the drivers to insert the tacks. The part 814^x has freely pivoted thereon segmental gears 872^x and 874^x which are engaged by rack-teeth formed on the sliding

bar 818^x which is positively reciprocated, as before described, by the pinion 822^x on the shaft 812^x. The segmental gears 872^x and 874^x also engage the bars 844^x and 848^x which are slidingly mounted in the part 814^x as above described. The bars 844^x and 848^x are connected by ball and socket joints with blocks 846^x and 850^x which are received in vertical guideways in the driver carrying arms 674^x and 676^x, see Fig. 31. The sliding bar 818^x is provided at its front end with forks or arms to embrace flanges on the sides of the driver carrying arm 672^x. By this arrangement when the bar 818^x is moved forwardly by the shaft 812^x the several driver carrying arms 672^x, 674^x, and 676^x are swung outwardly into positions somewhat remote from the edge of the last in order to give space for the grippers to act, and when said sliding bar 818^x is retracted the driver carrying arms are moved inwardly toward and over the last, into position for inserting the tacks through the pulled-over marginal portions of the upper for securing the upper to the inner-sole.

The driver carrying arms 672^x, 674^x, and 676^x, in their inward movement into position to insert the securing tacks, contact with unlatching devices 204, shown in Figs. 1 and 2, which form parts of the gripper mechanisms, and when pressed inwardly permit the grippers to descend for slackening the upper and to open for releasing the upper, as described in said application Serial No. 200,342. It is to be understood that prior to the opening of the grippers for releasing the upper the wiping and pressing devices heretofore described have engaged the upper at the sides and toe of the last and that these devices hold the upper from slipping back during the brief interval between the release of the upper from the grippers and the insertion of the securing tacks.

The securing tacks are supplied to the 110 tack inserting mechanisms by suitable tack tubes 586^x extending from a tack-feeding mechanism, hereinafter referred to, to a position on the forwardly projecting portion *b*⁴ of the machine head B, from which 115 position they discharge their tacks into conductors supported by the driver and tack carrying arms 672^x, 674^x, and 676^x, see Fig. 3.

The tack carrying and inserting mechanisms which are supported on the arms 674^x and 676^x at the opposite sides of the last are each arranged to insert two tacks. These mechanisms are swiveled in their swinging arms in order that they may be adjusted tangentially with relation to the portion of the edge of the last adjacent to which the tacks are to be inserted so that the two tacks shall be located a predetermined distance from the edge of the last. These mechanisms are duplicates of each other and, 120 125 130

therefore, a description of only one of them is necessary. The mechanism carried by the arm 674^x is shown in Figs 32 to 44 inclusive. The arm 674^x is chambered out on its inner side, the rear wall of the chamber being curved, as shown in Fig. 33, and the chamber receives a block 500, see Fig. 34, which is held in place by a ribbed retaining plate 502 secured to the lower end of the arm 674^x. The ribs of the retaining plate are received in grooves in the block, see Fig. 37, and this plate serves to hold the block against displacement either downwardly or outwardly. The block 500 has an arc-shaped rib 504 at its upper end, as shown in Fig. 34. This rib enters a guideway in the rear of a lug which depends from the upper end of the chamber in which the block 500 is located. The plate 502 and the lug securely hold the block 500 in place in its chamber. To hold the block 500 normally in its central position and to return it to such position after it has been turned laterally in either direction therefrom the arm 674^x is provided with a spring-pressed plunger 506 having a V-shaped end which takes into a correspondingly shaped recess in the upper end of the block. To the lower end of the carrier block 500 is secured the tack carrier 508, see Figs. 32, 35 and 37. The tack carrier has a rib 510 which is received in a groove 511 in the front side of the carrier block 500. The tack carrier has also an upwardly and backwardly standing tongue 512 which is received in a recess in the rear side of the block 500. A clamping bolt 514 passes through the rear portion of the block 500 and under the tongue 512 of the tack carrier 508 to clamp said tack carrier securely between the side wings of the block 500, as shown in Fig. 37.

The tack carrier is provided at its front with two independent tack holders 520, 520, see Figs 35, 36, and 40. The tack holders are duplicates and as here shown each comprises a block bored to form a driver guideway and to receive a tack. The tack is supported in the lower part of the tack holder by blocks 522, 522 having between them a tapering aperture for centering the tack. The blocks 522 are pivotally supported at 523 and their rear faces are beveled, as shown in Fig. 44. The beveled faces of the blocks are acted upon by the beveled faces of spring-pressed plungers 524, 524, see Figs. 37 and 44. The spring-pressed plungers hold the blocks yieldingly pressed together and return them to normal position, as shown in Fig. 42, after said blocks have been displaced laterally, as shown in Fig. 43, by the driver bar in inserting the tack.

The tacks are conducted from the tack tubes 586^x to the tack holders 520 by means of conductors 530 which are extended through recesses in the arm 674^x and the

block 500 and are connected to the arm 674^x by a pivot pin 532. The conductors have upwardly extending lugs 534, see dotted lines in Fig. 37, which are acted upon by spring-pressed plungers 536 for holding said conductors with their lower ends normally swung forward in position to deliver tacks into the tack holders. This arrangement permits the conductors to be moved by swinging their lower ends backwardly to give place to the drivers in the operation of inserting the tacks.

The drivers 540, of which there are two for each mechanism for inserting tacks at the side of a shoe, are carried by a driver block 542 which is pivoted upon the driver bar 544 by means of a pin 546, as shown in Figs. 36 and 37.

The tack holder 508 is provided on its lower side with a block 550 which is adjustably secured to the tack carrier by a bolt 552, as shown in Figs. 32 and 37. The front face of the block 550 presents a shoulder 554 adapted to contact with the shoulder 440 heretofore described as formed on the upper side of the wiper and presser carrier 424, see Figs. 37 and 41. The engagement of the shoulder 554 with the shoulder 440 as the arm 674^x is swung to move the tack carrying and inserting mechanism into operative position, after the wiper and presser have adjusted themselves to the edge of the last, results in automatically adjusting the tack carrier block and tack holders tangentially with relation to the edge of the last so that each of the two tacks will be inserted a predetermined distance from the edge of the last, as shown in Fig. 40. Usually it will be desired to insert the two tacks the same distance from the edge of the last, but they might be inserted different distances from the edge of the last if preferred by setting the block 554 in an angular position.

The driver bar 544 is guided in a groove 110 in the inner side of the arm 674^x. The driver block 542, swiveled on the lower end of the driver bar 544, is guided over the plane, front face of the swiveled carrier block 500 as said drivers descend, and inasmuch as the swiveled block 500 is adjusted angularly by the block 550 into alignment with the edge of the last, the driver block 542 will also be adjusted about its pivot simultaneously with the adjustment of the block 500 so that the drivers are kept at all times in alignment with the tack openings in the tack holders. The tack conductors 530 are moved backwardly by the drivers and driver block 542, as the drivers descend.

The invention is not limited to a construction in which the tack holders and driver blocks turn with relation to the arm 674^x as it is only essential to the invention that the holders and blocks be arranged to turn 130

relatively to some portion of their supporting means.

- The tacks are preferably driven in a direction inclined toward the center of the last 5 and to this end the openings in the tack holders are arranged obliquely to the bottom of the last and the drivers are caused to travel in a direction oblique to the bottom of the last. This is accomplished by 10 arranging the block 500 so that its driver guiding face will stand in the desired oblique line with relation to the bottom of the last. The driver bar is provided with an inclined face 560 and is guided through a 15 yoke 562 having a correspondingly inclined face to permit the driver bar to have the necessary movement in its groove in the arm 674^x while it is guided obliquely over the face of the block 500 in driving the tacks. 20 The insertion of tacks simultaneously at opposite sides of the last and in a direction inclined inwardly from the edge of the last causes the upper to be tightened evenly on the two sides of the last by the ingoing tacks. 25 The tacks are contained in a tack pot 400^x which is provided with suitable mechanism, not shown, for lifting the tacks and delivering them on the raceways 444^x, see Fig. 3. A clearing mechanism, indicated at 630, prevents the tacks from clogging in the raceways and suitable delivering mechanism, not shown, is provided by which the tacks are delivered singly into the tack tubes 584^x. 30 This escapement mechanism may be of any usual or well-known construction, and the clearer, together with its operating mechanism and actuating mechanism for the tack pot, constitutes the subject matter of an application about to be filed. 35
- The operation of pulling-over a shoe as carried out by this machine is briefly stated as follows: The shoe is presented by the workman bottom upwardly to the machine, with the inner-sole against the sole-rest and 40 with the outwardly and upwardly extending edges of the upper and lining materials between the open jaws of the grippers. The grippers are first closed to grip the upper and then raised to pull it about the last, the 45 last being held from upward movement by the sole-rest. Preferably the toe grippers are put into action first to pull and thereby straighten the upper longitudinally of the last, and then the side grippers are brought 50 into action to pull the sides of the upper and shape the upper to the last along the ball and instep part of the last. While the side grippers are still moving, the sole-rest carrier is rocked about its pivot by the cam 378^x 55 to depress the toe portion of the last against the tightly strained upper to sink the last downwardly into the upper and cause it to conform to the shape of the last. Thereafter the heel rest is moved forward into 60 supporting engagement with the heel end of

the last. The grippers actuating mechanism, the heel rest actuating mechanism, and the sole rest actuating mechanism are so timed that the grippers will first have pulled the upper enough to have pressed the shoe 70 firmly against the sole rest, and the depression of the last in the upper by the sole rest will have been completed, before the heel rest has advanced sufficiently far to engage the heel end of the last. If it is desired to move the inner-sole with relation to the last in the regular operation of the machine, the block 146 will have been adjusted so that its groove will form the desired angle with relation to the line of movement of the slide 80 10, according to the extent and direction of the movement desired for the inner-sole. The lever 152 will then be rocked to move the sole-rest, and therefore the inner-sole, while the grippers are pulling the upper 85 about the last. If the inner-sole is secured to the last when the shoe is assembled for pulling-over, as it usually is in the higher grades of work, including nearly all welt shoes, then the last as well as the inner-sole 90 will be moved longitudinally by the sole-rest. If it is desired to move the heel-rest positively forward for advancing the last near the end of the pulling-over operation, the pawl controller 82 will have been adjusted so that, as the lever 72 is rocked by the incline 70, the pawl 76 will be allowed to engage the ratchet wheel 80 before the end of the downward stroke of the pawl. 95 This will rotate the shaft 30 and move the heel-rest positively forward. If it is desired merely to lock the heel-rest against rearward movement without imparting to it any forward movement, the pawl controller 100 82 will have been adjusted so as to allow the pawl 76 to engage the ratchet wheel 80 just at the end of the downward stroke of the pawl. These operations having taken place, the machine is brought to rest to permit the workman to examine the shoe, and, if necessary, to shift the heel-rest or the sole-rest, or both of them, manually by means of the hand lever 160 to adjust the last and position the inner-sole, if, upon inspection, he finds that these operations have not been 105 completely and satisfactorily performed in the automatic operations of the machine. In that class of work, however, in which the inner-sole is tacked to the last, the inner-sole cannot, of course, be moved with relation to the last, but the sole-rest may be operated to move the inner-sole and last together either backwardly or forwardly in the upper, according to whether it is desired 110 to strain the upper forwardly or backwardly with relation to the last. While the machine is at rest the workman also examines the upper, and, if he finds that it is not properly positioned on the last, adjusts it 115 longitudinally about the last by means of 120 125 130

the hand lever 292^x, or transversely about the last by pulling down upon one or the other of the side gripper operating levers 154^x. When the machine is re-started the arms carrying the last supporting and wiping and pressing mechanisms are moved into position against the sides of the last by the cam N³³ acting on the slide N²⁶, and as the last supports and the wipers and pressers come into engagement with the upper on the sides of the last the grippers spreader is retracted to allow the grippers to be moved inwardly over the last by the springs 316^x to over-draw the upper. The arms supporting the fastener carrying and inserting mechanisms are moved inwardly over the last by the rearward movement of the slide bar 818^x. The fastener carrying and inserting mechanisms follow closely after the grippers in their inward movement over the last.

The wiping and pressing mechanisms at the sides of the last adjust themselves automatically according to the contour of the portions of the last engaged by them, and when the arms supporting the tack carrying and inserting mechanisms for the sides of the last move inwardly over the last the shoulders 554 on the swiveled tack carriers meet the shoulders 440 on the wiping and pressing mechanisms and thereby cause the swiveled tack carriers, and with them the drivers, to be positioned automatically for inserting the side tacks all the same distance from the edge of the last. Before the fastener carrying and inserting mechanisms reach the limit of their inward movement they contact with the unlatching devices of the several grippers mechanisms and cause the grippers to be opened for releasing the upper. The slide bar 818^x continues to move rearwardly for a short distance after the fastener carrying and inserting arms have reached the limit of their movement to withdraw the driver supporting shoulders thereof from under the coöperating shoulders 922^x, 928^x, and 930^x on the driver bars, thus permitting the driver bars to be depressed by their actuating spring 708^x acting through the lever 50 718^x and the plate 720^x for driving the tacks from the tack carriers into the upper and inner-sole to secure the upper in its pulled-over position. After the upper has been secured the arms carrying the last supporting and upper wiping and pressing mechanisms are separated to release the last and the sole-rest and the heel-rest are restored to their initial positions. The part 814^x is rocked downwardly by the cam 804^x and the slide 818^x is advanced to reëngage the shoulders carried by said slide with the coöperating shoulders on the drivers. The part 814^x is then rocked upwardly while the slide 818^x continues to advance thereby 65 to lift the drivers against the action of the

spring 708^x, and at the same time to spread the fastener carrying and inserting mechanisms apart. The forward movement of the slide 818^x also operates the grippers spreading mechanism to spread the grippers into positions for engaging the upper of the next shoe.

It will of course be understood that this invention is not limited to the specific embodiment thereof described and shown in this specification, but that the invention may be embodied in many different mechanical forms and that certain of its features are capable of advantageous use independently of other features.

Having thus described my invention, I claim as new and desire to secure by Letters Patent of the United States:—

1. A pulling-over machine having means for gripping an upper at the end and opposite sides of the forward portion and pulling it over a last, in combination with a heel-rest movable laterally with relation to the last for adapting it to engage heels of different lasts.

2. A pulling-over machine having, in combination, means for gripping an upper at the toe and at opposite sides of the fore-part and pulling it over a last, a rest for the heel of the last, and means for automatically pressing said rest forwardly into position to support the last against longitudinal rearward displacement by the toe pulling means.

3. A pulling-over machine having, in combination, for gripping an upper at the toe end and at opposite sides of the fore part and pulling it over a last, a heel-rest, and yielding actuating mechanism operatively connected with the pulling means for moving the heel-rest into position to hold the last against rearward displacement by the pulling means.

4. Means for gripping an upper and pulling it over a last, a rest for the bottom of the last, a rest for the heel of the last, and actuating mechanism adapted to position the heel-rest automatically for supporting lasts of varying sizes.

5. In a pulling-over machine, means for pulling an upper over a last, in combination with a laterally movable heel-rest and means for locking said heel-rest against displacement.

6. Means for pulling an upper over a last, and a rest for the bottom of the last, in combination with a rest for the heel of the last, means for moving the heel-rest into position to support the heel of the last, and means for additionally moving the heel-rest to force the last farther into the upper.

7. In a pulling-over machine, means for pulling an upper over a last, and a rest for the bottom of the last, in combination with a rest for the heel of the last, means for

5 moving the heel-rest into position to support the heel of the last, means for additionally moving the heel-rest to force the last farther into the upper, and a controller to vary the amount of said additional movement.

10 8. In a pulling-over machine, means for gripping an upper at the toe end and at opposite sides of the forward portion of the shoe and pulling the upper over a last, in combination with a rest for supporting the heel end of the last, and means for actuating said rest to move the last longitudinally into the forward portion of the upper held by the gripping means.

15 9. Means for pulling an upper over a last, a rest for the bottom of the last, a rest for the heel of the last, automatic means for actuating the heel-rest, and manually controlled means for further moving the heel-rest.

20 10. In a pulling-over machine, means for pulling an upper over a last, a rest for the bottom of the last, a rest for the heel of the last, automatic means for actuating the heel-rest, means for locking said heel-rest against return movement, and manually controlled means for further moving the heel-rest.

25 11. In a pulling-over machine, means for gripping an upper at the toe end and at opposite sides of the forward portion and pulling it over a last, a rest for the heel of the last, and means for sustaining the heel-rest movably to permit automatic lateral adjustment of the rest according to the position of the heel of the last in a substantially right line after the position of the last has been determined by the tension of the pulling means upon the upper.

30 40 12. In a pulling-over machine, means for pulling an upper over a last, and a swinging heel-rest laterally adjustable in a direction substantially at right angles to the length of the last to adapt it to support lasts having their heels differently positioned.

35 45 13. In a pulling-over machine, means for pulling an upper over a last, in combination with last supporting means having inclined contact faces for engaging opposite sides of the last, and means for automatically actuating said supporting means into engagement with the last, said supporting means being automatically adjustable laterally according to the position of the portion of the last engaged thereby.

50 55 14. In a pulling-over machine, means for pulling an upper over a last, in combination with means for supporting the last, said supporting means being automatically adjustable according to the position of the portion of the last engaged thereby, and automatic means for locking said supporting means in adjusted position.

60 65 15. In a pulling-over machine, means for pulling an upper over a last, a rest for the

heel of the last arranged for lateral movement to adapt it to the position of the heel end of the last which is to be rested, means for moving the heel-rest longitudinally into position for resting the last, and means for locking the heel-rest against lateral movement while it is supporting the last.

16. In a pulling-over machine, means for pulling an upper over a last, in combination with a laterally movable heel-rest automatically adjusted laterally according to the position of the heel of the shoe, means for automatically locking said heel-rest against lateral displacement while it is supporting the shoe, and means for automatically unlocking said heel-rest when the shoe is removed.

17. In a pulling-over machine, means for gripping an upper at the end and opposite sides of the forward portion and pulling it over a last, in combination with a swinging rest for the heel of the last arranged for automatic bodily movement laterally by the engagement of the shoe therewith.

18. In a pulling-over machine, means for pulling an upper over a last, a movable heel-rest adapted to be adjusted laterally according to the position of the shoe, means for locking said heel-rest in adjusted position, and means for unlocking the rest when the shoe is removed therefrom.

19. In a pulling-over machine, the combination with a movable heel-rest and a block provided with members adapted to be interlocked for holding the heel-rest against movement, of means by which the rest and block are relatively moved to interlock said members when the rest engages a shoe.

20. In a pulling-over machine, a swinging heel-rest and a relatively fixed part provided with members adapted to be interlocked for holding the heel-rest against swinging movement.

21. In a pulling-over machine, means for pulling an upper over a last, a rest for the heel of the last, yielding actuating mechanism for moving the rest into engagement with the last, and positively actuated means for moving the heel-rest and the last.

22. In a pulling-over machine, means for pulling an upper over a last, a rest for the heel of the last, means for actuating said rest to move the last, and means for adjusting the extent of said movement.

23. In a pulling-over machine, means for pulling an upper over a last, a rest for the heel end face of the last, a carrier upon which said rest is movable, and means for locking said rest in adjusted position in its carrier.

24. In a pulling-over machine, the combination with means for pulling an upper over a last, of a heel-rest, a support, and parallel links by which the heel-rest is suspended from its support for lateral move-

- ment while maintaining its approximately upright position.

25. In a pulling-over machine, means for pulling an upper over a last, in combination with manually controlled means for relatively moving the last and pulled upper in a direction longitudinal of the last. 70

26. In a pulling-over machine, means for pulling an upper over a last, in combination with means for sinking the last into the pulled upper, and manually controlled means for moving the last longitudinally in the pulled upper. 10

27. In a pulling-over machine, means for pulling an upper over a last, in combination with a rest for the heel of the last and mechanism to actuate the rest for moving said last in a direction approximately perpendicular to the line of strain of the pulling means. 15

28. In a pulling-over machine, means for pulling an upper over a last having an inner-sole on its tread face, in combination with means for adjusting the inner-sole either forwardly or backwardly with relation to the upper. 20

29. In a pulling-over machine, means for pulling an upper over a last, means for engaging an inner-sole on the tread face of the last, and mechanism for actuating said engaging means to move the inner-sole either forwardly or backwardly with relation to the upper. 30

30. In a pulling-over machine, means for pulling an upper over a last, a sole-rest for engaging an inner-sole on the tread face of the last, automatic means for actuating the sole-rest to move the inner-sole with relation to the upper and means under control of the operator for rendering said actuating means inoperative. 35

31. In a pulling-over machine, means for pulling an upper over a last, combined with means for moving an inner-sole in the desired direction to position it properly upon the last. 40

32. In a pulling-over machine, the combination with a rest for the heel of the last, of means for engaging an inner-sole upon the tread face of the last, and means for actuating one of said parts for moving the inner-sole and last relatively. 45

33. Means for pulling an upper over a last, in combination with automatic means adapted for moving an inner-sole upon the last, said means being arranged for adjustment to move the inner-sole either forwardly or backwardly. 50

34. Means for pulling an upper over a last having an inner-sole on its tread face, in combination with automatic means for relatively moving the last and the inner-sole longitudinally of the last, said automatic means being adjustable for changing the direction of the movement effected. 55

35. Means for pulling an upper over a last having an inner-sole on its tread face, in combination with manually operated means for relatively moving the last and the inner-sole longitudinally of the last. 60

36. In a pulling-over machine, means for pulling an upper over a last, in combination with manually operated means adapted for moving an inner-sole either backwardly or forwardly over the last. 70

37. In a pulling-over machine, means for pulling an upper over a last, and a rest for engaging the inner-sole of the shoe to sustain the shoe against displacement by the pulling means, in combination with mechanism arranged to be adjusted for actuating said rest to move the inner-sole either forwardly or backwardly with relation to the last. 75

38. Means for pulling an upper over a last and means for engaging an inner-sole, in combination with mechanism for automatically moving said engaging means to shift the inner-sole upon the last, and manually controlled means for imparting an additional movement to the inner-sole. 80

39. In a pulling-over machine, means for engaging an inner-sole and actuating mechanism therefor, said actuating mechanism being adjustable for causing the engaging means to move the inner-sole automatically either backwardly or forwardly in the pulled upper during the operation of the machine. 85

40. In a pulling-over machine, means for pulling an upper over a last, in combination with means for moving an inner-sole with relation to the last, said last-mentioned means being adjustable to vary the direction of the movement imparted by it. 90

41. In a pulling-over machine, means for pulling an upper over a last, in combination with a rest for engaging an inner-sole, means for actuating said rest to move the inner-sole either forwardly or backwardly over the last, and means for restoring said rest to normal position. 100

42. A pulling-over machine comprising means for pulling an upper over a last, and for sinking the last into the upper, said machine also having provision for independently moving an inner-sole over the last. 105

43. A pulling-over machine comprising means for pulling an upper over a last, and for adjusting the pulled upper about the last, in combination with means for adjusting an inner-sole on the last. 110

44. In a pulling-over machine, means for pulling an upper over a last, and for adjusting the pulled upper about the last, in combination with means for adjusting an inner-sole on the last, and means for securing the upper to the inner-sole. 115

45. In a pulling-over machine, means for pulling an upper over a last, a rest for engaging an inner-sole and a rest for engaging 120

- the heel of the last, and means for moving said rests together.
46. A pulling-over machine comprising means for pulling an upper over a last, a rest for engaging an inner-sole, a rest for the heel of the last, and means for moving said two rests together, said machine also having provision for relatively moving said rests.
47. In a pulling-over machine, a rest comprising laterally extending arms for engaging an inner-sole near its edges and a forwardly extending arm, said forwardly extending arm having an adjustable foot-piece for engaging the inner-sole near its end, and means for adjusting said foot-piece toward and from the plane of the bottom of the last.
48. A pulling-over machine comprising means for pulling an upper over a last, a rest for the heel of the last, and automatic means for actuating said rest to move the last, said machine also having provision for rendering said actuating means inoperative to discontinue the automatic movements of the last by the heel-rest.
49. A pulling-over machine comprising means for pulling an upper over a last having an inner-sole on its tread face, and a rest for engaging the inner-sole, in combination with mechanism for actuating said rest to move the inner-sole with relation to the last, said machine also having provision for rendering said actuating mechanism inoperative when desired.
50. A pulling-over machine comprising means for pulling an upper over a last, a sole-rest for engaging an inner-sole on the tread face of the last, a rest for the heel of the last, and manually controlled means for moving the sole-rest, said machine also having provision for connecting the manually controlled means to the heel-rest whereby the heel-rest also may be moved manually.
51. In a pulling-over machine, means for pulling an upper over a last, a sole-rest for engaging an inner-sole on the tread face of the last, a rest for the heel of the last, actuating mechanism for said heel-rest, manually operated means for actuating the sole-rest, a pawl carried by said manually operated means, and means under the control of the workman for connecting said pawl with the heel-rest actuating mechanism.
52. In a pulling-over machine, the combination with means for pulling an upper over a last, said machine having provision for adjusting the upper upon the last, of a rest for engaging an inner-sole, a rest for the heel of the last, and manually controlled means for relatively moving said rests.
53. In a pulling-over machine, the combination with means for pulling an upper over a last, a sole-rest, and a rest for the heel of the last, of manually operated means for actuating the sole-rest and the heel-rest, said means comprising a pawl normally connected with the sole-rest actuating mechanism, and means under the control of the operator for disconnecting said pawl from said sole-rest actuating mechanism.
54. In a pulling-over machine, means for pulling an upper over a last, in combination with means for supporting the last, said supporting means being automatically adjustable according to the position of the portion of the last engaged thereby, and means for automatically locking said supporting means in adjusted position.
55. In a pulling-over machine, means for supporting a side of the last and means for wiping an upper over the last, combined with a movable connection between said two means arranged to advance the wiping means toward the last as the supporting means is depressed.
56. In a pulling-over machine, means for supporting a last and means for pressing an upper down upon the last, combined with a movable connection between said two means arranged to move the pressing means automatically toward the last as the supporting means is depressed.
57. In a pulling-over machine, means for supporting a last and means for wiping an upper over the last, combined with mechanism whereby one of said means is caused to actuate the other means with relation thereto.
58. In a pulling-over machine, means for supporting a last and means for pressing an upper down upon the last, combined with mechanism whereby one of said means is caused to actuate the other.
59. In a pulling-over machine, means for supporting a last and means for wiping an upper over the last, combined with connecting mechanism intermediate the supporting means and the wiping means whereby when the supporting means meets the last the wiping means is moved with relation to the supporting means to advance it.
60. In a pulling-over machine, means for supporting a last and means for wiping an upper over the last, combined with connecting mechanism intermediate the supporting means and the wiping means whereby when the supporting means meets the last the wiping means is advanced with relation to the supporting means, and means for automatically restoring the parts to normal position when they are withdrawn from engagement with the shoe.
61. In a pulling-over machine, means for supporting a last and means for wiping an upper over the last, combined with mechanism comprising relatively movable parts connecting said two means and arranged to transmit power from the last supporting means to the wiping means.

whereby the latter is actuated with a force bearing a predetermined ratio to the pressure against the supporting means.

62. In a pulling-over machine, means for supporting a last and means for forcing an upper into pulled-over position, combined with a carrier upon which the two means are relatively arranged for causing the supporting means to engage the shoe before the other means, and mechanism whereby the supporting means is caused thereafter to advance said other means into engagement with the shoe.

63. In a pulling-over machine, means for wiping an upper over the last, means for pressing the wiped upper down upon the inner-sole, and a movable connection between said wiping and pressing means whereby the latter is actuated by the former.

64. In a pulling-over machine, means for wiping an upper over a last and pressing the wiped upper down upon the inner-sole of the shoe, said means comprising a movable wiper and a rocking presser and connections whereby the presser is actuated by the wiper.

65. In a pulling-over machine, means for wiping an upper over a last and pressing the wiped upper down upon the inner-sole, said means comprising a presser and a wiper and a connection whereby the wiper operates the presser, an actuator for said wiper, and means for restoring the wiper to normal position when it is withdrawn from the shoe.

66. In a pulling-over machine, means for wiping and pressing an upper over a last, said means comprising a carrier, a wiper and presser independently mounted on said carrier, and a connection between said wiper and presser, whereby the latter is actuated by the former.

67. In a pulling-over machine, means for wiping and pressing an upper over a last, said means comprising a carrier, a wiper and a presser movably mounted on said carrier, and a connection between said wiper and presser whereby the presser is actuated by the wiper, in combination with means for actuating said carrier whereby the wiper is brought into wiping engagement with the upper, said wiper having provision for yielding backwardly in the carrier to impart to the presser an independent movement to bring it into pressing engagement with the upper.

68. In a pulling-over machine, means for supporting a last and means for wiping and pressing an upper over a last, said last-mentioned means comprising a carrier, a wiper and a presser movably mounted in said carrier, and a connection between said wiper and presser by which the presser is actuated by the wiper, in combination with mechanism connecting said supporting

means with said carrier, said parts being so arranged that when the supporting means meets the last it may yield backwardly for actuating said carrier through said connecting mechanism, whereby the wiper and presser are brought into operative engagement with the upper.

69. In a pulling-over machine, means for wiping and pressing an upper over a last, said means comprising a carrier, a wiper slidably mounted in said carrier and provided with means for normally holding it in advanced position, and a presser movably mounted on said carrier and having an arm to be engaged by the wiper, whereby when the wiper comes into engagement with the upper it is moved and actuates the presser for bringing the presser into engagement with the upper.

70. In a pulling-over machine, a wiper, a carrier in which the wiper is yieldingly mounted, a presser mounted on said carrier for movement in a plane approximately perpendicular to the plane of movement of the wiper, a connection between said wiper and said presser, whereby, as the wiper engages the upper to wipe it toward the edge of the last and yields backwardly, the presser is automatically moved downwardly to press the wiped-up portion of upper down upon the bottom of the last.

71. In a machine of the class described, tack driving mechanism, a tack carrier adapted to hold a plurality of tacks, means to move said carrier to present the tacks for the operation of the driving mechanism, and means governed by the position and shape of the last for positioning said tack carrier tangentially with relation to the edge of the last to present the tacks each at a predetermined distance from the edge of the last.

72. In a machine of the class described, tack driving mechanism, a tack carrier adapted to hold a plurality of tacks, and means to move said carrier to present the tacks for the operation of the driving mechanism, said carrier being arranged to be adjusted during said movement according to the contour of the last.

73. In a machine of the class described, tack driving mechanism, a tack carrier adapted to hold a plurality of tacks, means to move said carrier over the last, said carrier and said driving mechanism being arranged to be adjusted during said movement according to the contour of the last whereby the several tacks are presented and inserted at predetermined distances from the edge of the last.

74. In a machine of the class described, tack driving mechanism, a tack carrier adapted to hold a plurality of tacks, means to move said carrier to present the tacks for the operation of the driving mechanism,

- 5 said carrier being arranged to be adjusted during said movement according to the contour of the last, and means controlled as to position by the contour of the last for effecting said adjustment of the tack carrier.
75. In a machine of the class described, tack driving mechanism, a tack carrier adapted to hold a plurality of tacks, means to move said carrier over the last, said carrier and said driving mechanism being arranged to be adjusted during said movement according to the contour of the last whereby the several tacks are presented and inserted at predetermined distances from 10 the edge of the last, and means controlled as to position by the contour of the last for effecting said adjustment of the tack carrier.
76. In a machine of the class described, tack-driving mechanism, a tack carrier adapted to hold a plurality of tacks, means to move the tack carrier over the last bottom for presenting the tacks to the operation of the driving mechanism, and means for adjusting the tack carrier angularly 15 with relation to the edge of the last to cause it to present the tacks at predetermined relative distances from the edge of the last.
77. In a machine of the class described, a tack carrier support, means for moving said support and the last relatively to place the tacks over the work, a tack carrier movably mounted in said support, and means for moving said carrier in its support to position it with relation to the last.
- 35 78. In a machine of the class described, a tack carrier support, a tack carrier adapted to hold a plurality of tacks, said tack carrier being movably mounted in said support, means for moving said support and 40 the last relatively to place the tacks over the work, and means for moving said tack carrier in its support to position it with relation to the last so that the tacks shall be presented each at a predetermined distance 45 from the edge of the last.
79. In a machine of the class described, a tack carrier support, a tack carrier movably mounted in said support and adapted to hold a plurality of tacks, in combination 50 with means controlled as to position by the contour of the last for positioning the tack carrier in its support to cause it to present the tacks each at a predetermined distance from the edge of the last.
- 55 80. In a machine of the class described, a tack carrier support, a tack carrier adapted to hold a plurality of tacks, means to move said support to bring the carrier over the bottom of the last, and means co-operating 60 with said carrier for positioning it to present the tacks each at a predetermined distance from the edge of the last.
81. In a machine of the class described, the combination with means controlled as to 65 position by the contour of the edge of the work, of a tack carrier support, means for actuating the support to move the carrier toward and from the work, and a tack carrier freely movable in said support and arranged to be positioned tangentially with 70 relation to the edge of the work by engagement with said means.
82. In a machine of the class described, a support, a tack carrier movably mounted in said support and adapted to hold a plurality of tacks, means to actuate said support to move the tack carrier over the last, means whereby said tack carrier is adapted to position itself automatically with relation to the edge of the last, a plurality of drivers 75 adapted to be positioned automatically with the said movable tack carrier, and means for actuating said drivers.
83. In a machine of the class described, a support, a tack carrier swiveled in said support and adapted to hold a plurality of tacks, means to actuate said support to move the tack carrier over the last, means whereby said tack carrier is adapted to position itself automatically with relation to the 80 edge of the last, a plurality of drivers adapted to turn with said swiveled tack carrier, and means for actuating said drivers.
84. In a machine of the class described, a swiveled tack carrier arranged to hold a plurality of tacks, a driver head adapted to turn with said tack carrier and provided with a plurality of drivers, and means for actuating the drivers.
85. In a pulling-over machine, means for pulling an upper over a last, fastener inserting mechanism, automatic means for moving said mechanism into operative position over the bottom of the last, means to limit the movement of said mechanism according to the size of the last and to cause said mechanism to position itself in accordance with the contour of the edge of the last.
- 100 86. In a pulling-over machine, means for pulling an upper over a last, movably mounted fastener inserting mechanism adapted to be positioned axially in accordance with the contour of the edge of the last and arranged to insert fastenings with 105 the points directed away from the edge of the last.
87. In a machine of the class described, a sole-rest, mechanism arranged for automatically moving the sole-rest in the regular operation of the machine, a part arranged for manual operation to move the sole-rest independently of the regular operation of the machine, and a device for disconnecting the automatic actuating mechanism for the 110 sole-rest to permit the independent operation of the sole-rest by said manually operated part.
88. In a machine of the class described, a heel-rest, actuating mechanism therefor, a 115

sole-rest, mechanism arranged for automatically moving the sole-rest in the regular operation of the machine, a part arranged for manual operation to move the sole-rest independently of the regular operation of the machine, a device for disconnecting the automatic actuating mechanism for the sole-rest to permit the independent operation of the sole-rest by said manually operated part, and means controlled by said device for connecting said manually operated part with the heel-rest actuating mechanism, at the will of the operator whereby both the sole-rest and the heel-rest may be moved by said manually operated part.

89. A pulling-over machine comprising means for gripping an upper and pulling it over a last, a rest for engaging and supporting the heel end of the last, and means for moving the rest into supporting position after the initial pull by the grippers has determined the position of the last, said rest having provision for automatic movement in a substantially right line for supporting lasts presented in different relations thereto.

90. In a pulling-over machine, means for gripping an upper and pulling it over a last, in combination with a rest for the end of the last, and means for supporting the rest for bodily movement laterally in a substantially right line with relation to the last for adjusting it to varying lasts.

91. In a pulling-over machine, a sole-rest and mechanism for actuating it, said actuating mechanism comprising a lever, connections between the lever and the sole-rest, and a reciprocating slide provided with means for operating the lever.

92. In a pulling-over machine, a sole-rest and mechanism for actuating it, said actuating mechanism comprising a lever, connections between the lever and the sole-rest, and a reciprocating slide provided with means for operating said lever, said means being adjustable to vary the operation of the lever.

93. In a pulling-over machine, a heel-rest and mechanism for actuating it, said actuating mechanism comprising a lever, adjustable connections between said lever and the heel-rest, and a reciprocating slide provided with means for operating the lever.

94. In a pulling-over machine, a sole-rest, actuating mechanism therefor comprising a hand lever, a heel-rest, actuating mechanism therefor, and means arranged to be operated by the workman for connecting the hand lever to the heel-rest actuating mechanism, whereby the sole-rest and the heel-rest may be moved together.

95. In a pulling-over machine, a sole-rest, actuating mechanism therefor comprising a shaft, a hand lever connected to the shaft, a heel-rest, actuating mechanism therefor, and

means including a pawl and ratchet arranged to be operatively connected at the will of the workman for putting the heel-rest actuating mechanism under the control of the hand lever, whereby said two rests may be actuated simultaneously when desired.

96. In a pulling-over machine, a sole-rest, automatic actuating mechanism therefor, a hand lever operatively connected with said sole-rest and held against movement independent of said automatic actuating means, a heel-rest, actuating mechanism therefor including a ratchet, the hand lever being provided with a pawl normally held out of engagement with the ratchet, and means arranged to be operated by the workman for disconnecting the hand lever from said sole-rest actuating means to permit the sole-rest to be actuated by said lever, said disconnecting means being arranged to be further operated for permitting the pawl on the hand lever to engage the ratchet of the heel-rest actuating mechanism to permit both of said rests to be moved by the hand lever.

97. A pulling-over machine having, in combination, a rest for the bottom of a last, grippers to engage an upper at opposite sides of the shoe and pull it over the last simultaneously from the two sides whereby the action of each gripper serves to resist lateral displacement of the shoe by the action of the other gripper, a gripper to engage the upper at the toe of the shoe and draw it backwardly over the toe end of the last, and a heel rest to resist rearward displacement of the shoe and which is movable laterally to adapt its position to that of the heel end of right and left crooked lasts and is yieldingly pressed forwardly to adapt its holding position automatically to the length of the shoe.

98. A pulling-over machine having, in combination, a rest for the bottom of a last, grippers to engage an upper at opposite sides of the shoe and pull it over the last simultaneously from the two sides whereby the action of each gripper serves to resist lateral displacement of the shoe by the action of the other gripper, a gripper to engage the upper at the toe of the shoe and draw it backwardly over the toe end of the last, and a heel rest to resist rearward displacement of the shoe and which is movable laterally to adapt its position to that of the heel end of right and left crooked lasts and is yieldingly pressed forwardly to adapt its holding position automatically to the length of the shoe, said machine having provision for independent manual actuation of the heel rest lengthwise of the shoe without disturbing the tension with which the rest is yieldingly pressed forwardly.

99. A pulling-over machine having, in

combination, a rest for the bottom of a last, grippers to engage an upper at opposite sides of the shoe and pull it over the last simultaneously from the two sides whereby the action of each gripper serves to resist lateral displacement of the shoe by the action of the other gripper, a gripper to engage the upper at the toe of the shoe and draw it backwardly over the toe end of the last, a heel rest to resist rearward displacement of the shoe and which is movable laterally to adapt its position to that of the heel end of right and left crooked lasts and is yieldingly pressed forwardly to adapt its holding position automatically to the length of the shoe, and additional means permitting adjustment of the heel-rest lengthwise of the shoe.

100. A pulling-over machine having, in combination, a rest for the bottom of a last, grippers to engage an upper at opposite sides of the shoe and pull it over the last simultaneously from the two sides whereby the action of each gripper serves to resist lateral displacement of the shoe by the action of the other gripper, a gripper to engage the upper at the toe of the shoe and draw it backwardly over the toe end of the last, and a heel-rest to resist rearward displacement of the shoe, said machine having provision for lateral right line movement of the heel-rest to adapt it to right and left lasts, and also provision for securely maintaining the rest in such lateral position during the pulling-over operation.

101. A pulling-over machine having, in combination, a rest for the bottom of a last, grippers to engage an upper at opposite sides of the shoe and pull it over the last simultaneously from the two sides whereby the action of each gripper serves to resist lateral displacement of the shoe by the action of the other gripper, and mechanism for inserting fastenings simultaneously at opposite sides of the shoe in directions inclined at an oblique angle inwardly toward the median line of the last, the inclination at one side being opposed to that at the other side to prevent lateral displacement of the last.

102. In a machine of the class described, the combination with means for supporting a last, and means for wiping an upper over the last, of means for driving tacks in front of the wiper into a portion of the upper not held thereby and in a direction inclined inwardly whereby such ingoing tack serves to tighten such free portion of the upper.

103. In a machine of the class described, the combination with means for supporting a last and means for wiping an upper over the last at opposite sides of the shoe, of means for driving tacks simultaneously at the two sides of the last into the upper in front of the wipers and in a direction inclined inwardly from the edge of the shoe whereby

any slack in said free portions of the upper is tightened by the ingoing tacks.

104. In a pulling-over machine, means for pulling an upper over a last, in combination with manually controlled means engaging the forepart of the last and adapted for operation to move the last rearwardly with relation to the gripped upper.

105. In a machine of the class described, means for working an upper over a last having an inner-sole on the tread face of the last, means for engaging the inner-sole, and mechanism for actuating said engaging means either forwardly or backwardly to move the inner-sole with relation to the upper.

106. A pulling-over machine having, in combination, pulling-over means, and shoe supporting means which includes a rest for the heel end face of the last.

107. A pulling-over machine having, in combination, pulling-over means, and shoe supporting means which includes a rest for the heel end face of the last mounted for lateral movement to adapt its position to the lateral position of the heel portion of different lasts the foreparts of which are located in substantially the same relation to the pulling-over means.

108. A pulling-over machine having, in combination, pulling-over means, shoe supporting means which includes a rest for the heel end face of the last mounted for lateral movement to adapt its position to the lateral position of the heel portion of different lasts the foreparts of which are located in substantially the same relation to the pulling-over means, and means for yieldingly pressing the rest forwardly to adapt it automatically to the length of different lasts.

109. A pulling-over machine having, in combination, pulling-over means, automatic actuating mechanism operatively connected therewith, and a heel rest which is mounted for automatic movement laterally to support heels of differently formed lasts the foreparts of which may be positioned in substantially the same relation to the pulling-over means.

110. A pulling-over machine having, in combination a toe gripper, side grippers, a rest shaped to embrace the heel end of the shoe, a last bottom rest, means for relatively actuating the grippers and the last bottom rest to stretch the upper and mountings for the toe gripper and the heel rest arranged to permit relative lateral adjustment of said gripper and rest to adapt the machine for use on right and left shoes.

111. A pulling-over machine having, in combination, a toe gripper, side grippers, a rest shaped to embrace the heel end of the shoe, a last bottom rest, means for relatively actuating the grippers and the last bottom rest to stretch the upper and mountings for

the grippers and for the heel end rest arranged to permit relative adjustment of said heel end rest and said toe and side grippers to position them for right and left crooked 5 lasts.

112. A pulling-over machine having, in combination, pulling-over means and shoe supporting means which includes a rest 4 shaped to embrace the heel end of the shoe 10 and bear upon the shoe at points spaced apart and located at either side of the shoe, said rest being formed to receive between said bearing points the usual shoe assembling tack which may project from the middle portion of the heel end. 15

113. A machine of the class described having, in combination, means for working an upper over a last, means for positioning the last vertically and a heel rest provided 20 with a recess adapted to receive the usual shoe assembling tack which projects from the rear end face of the shoe.

114. A machine of the class described having, in combination, means for working 25 the upper of an assembled shoe over a last, means for positioning the last vertically, and a heel rest shaped to embrace the heel end of a shoe and having a vertically elongated recess to receive the usual shoe assembling 30 tack which projects from the rear end face of the shoe and which may be located varying distances from the plane of the shoe bottom.

115. In a machine of the class described, 35 the combination with grippers for pulling an upper about a last, of a presser, a wiper, a depressible support for the last, means for releasing the grippers from the upper, and means for actuating the wiper to wipe the 40 upper over the side of the last and thereafter to cause the presser to press the wiped upper down upon the innersole before the grippers are released.

116. In a machine of the class described, 45 the combination with grippers for pulling an upper about a last, of a presser, a wiper, means for releasing the grippers from the upper, and means for actuating the wiper to wipe the upper over the side of the last and 50 thereafter to cause the presser to press the wiped upper down upon the innersole before the grippers are released.

117. In a pulling-over machine, the combination with a shoe rest, of automatic actuating mechanism therefor, comprising a 55 pawl and a ratchet, and a device arranged to be adjusted for holding the pawl out of engagement with the ratchet for a variable time according to the amount of movement to be imparted to the rest. 60

118. A machine of the class described having, in combination, means for working an upper over a last, and means for engaging the innersole on the last bottom to prevent displacement of the work by the overworking means and comprising the feet to engage the forepart of the shoe at either side over the ball, the foot to engage the toe of the shoe, and means to permit relative adjustment of said feet for shoes of different sizes 70 and to lock the parts in definite adjusted positions separated by uniform distances. 75

119. A machine of the class described having, in combination, means for working an upper over a last, and means for engaging 75 the innersole on the last bottom to prevent displacement of the work by the overworking means, and comprising the feet to engage the forepart of the shoe at either side over the ball, the foot to engage the toe of 80 the shoe, mountings arranged to permit bodily adjustment of the shoe engaging means through definite spaces, and means arranged to assist the operator in making relative adjustments of the feet through definite spaces. 85

120. A machine of the class described having, in combination, means for working an upper over a last, and means for engaging the innersole on the last bottom to prevent displacement of the work by the overworking means, and comprising the side feet 124, 124 and the end foot 126 arranged for endwise adjustment between the side feet and provided with regularly spaced recesses, and the spring pressed latch 128 adapted to take 95 into one or another of said recesses to lock the end rest in predetermined positions. 90

In testimony whereof I have signed my name to this specification in the presence of two subscribing witnesses.

RONALD F. McFEELY.

Witnesses:

NELSON W. HOWARD,
WILLIAM B. PIERCE.

It is hereby certified that in Letters Patent No. 1,029,387, granted June 11, 1912, upon the application of Ronald F. McFeely, of Beverly, Massachusetts, for an improvement in "Pulling-Over Machines," an error appears in the printed specification requiring correction as follows: Page 18, line 113, after the word "and" insert the word *means*; and that the said Letters Patent should be read with this correction therein that the same may conform to the record of the case in the Patent Office.

Signed and sealed this 23rd day of July, A. D., 1912.

[SEAL.]

C. C. BILLINGS,
Acting Commissioner of Patents.
